(57) **CLAIM**

The ornamental design for a portable battery charger with solar cells, as shown and described.

DESCRIPTION

FIG. 1 is a front view of a first embodiment of a portable battery charger with solar cells showing our new design; FIG. 2 is a top view thereof;

FIG. 3 is a right side view thereof;

FIG. 4 is a bottom view thereof;

FIG. 5 is an enlarged sectional view taken along line 5-5 in FIG. 1;

FIG. 6 is a front view showing the solar cells in a deployed state;

FIG. 7 is a top view showing the deployed state;

FIG. 8 is a right side view showing the deployed state;

FIG. 9 is a left side view showing the deployed state;

FIG. 10 is a rear view showing the deployed state;

FIG. 11 is a bottom view showing the deployed state;

FIG. 12 is a front view of a second embodiment of the portable battery charger with solar cells showing our new design;

FIG. 13 is a top view thereof;

FIG. 14 is a right side view thereof;

FIG. 15 is a bottom view thereof;

FIG. 16 is an enlarged sectional view taken along line 16-16 in FIG. 12;

FIG. 17 is a front view showing the solar cells in a deployed state;

FIG. 18 is a top view showing the deployed state;

FIG. 19 is a right side view showing the deployed state;

FIG. 20 is a left side view showing the deployed state;

FIG. 21 is a rear view showing the deployed state; and,

FIG. 22 is a bottom view showing the deployed state.

The broken lines in the figures depict portions of the article which form no part of the claimed design.
